COOPERATING FIRING AND INDEXING DEVICES
FOR REVOLVER-TYPE FIREARMS

Frederick P. Reed, Ludlow, Mass., assignor to the United States of America as represented by the Secretary of the Army

Filed Aug. 23, 1962, Ser. No. 219,085

7 Claims. (Cl. 89—155)

(Granted under Title 35, U.S. Code (1952), sec. 266)

The invention described herein may be manufactured and used by or for the Government for governmental purposes without the payment to me of any royalty thereon.

This invention relates to firearms of the revolver-type and more particularly to the devices for firing such firearms and for successively indexing the chambered cylinder.

It is one object of this invention to provide a revolver-type firearm which is of sound structure and positive in operation and which is inexpensive to manufacture.

It is another object of this invention to provide a revolver-type firearm which utilizes setback of a fired cartridge case by blow-back action to energize the bolt assembly so as to perform the cyclic functions of cocking the firing pin thereof and assist in indexing the cylinder to align the next successive chamber therein with the barrel.

The specific nature of the invention as well as other objects and advantages thereof will clearly appear from a description of a preferred embodiment as shown in the accompanying drawings in which:

FIG. 1 is a longitudinally cross-sectioned view of a revolver-type firearm showing the firing pin cocked and the cylinder indexed in firing position by the bolt;

FIG. 2 is a view taken along line 2—2 of FIG. 1;

FIG. 3 is a view taken along line 3—3 of FIG. 1;

FIG. 4 is a view taken along line 4—4 of FIG. 1;

FIG. 5 is a view similar to FIG. 1 but showing the fired case set back to energize the bolt assembly;

FIG. 6 is a view taken along line 6—6 of FIG. 2 and shows the indexing pawl held disengaged from the cylinder by the front member of the bolt assembly;

FIG. 7 is a view similar to FIG. 6 but showing the indexing pawl freed to engage one of the notches in the cylinder; and

FIG. 8 is a view taken along line 8—8 of FIG. 7.

Shown in the figures is a firearm 12 having a tubular receiver 14 in which a bolt assembly 16 is slidably mounted for longitudinal travel. Depending from receiver 14 is a pistol grip 18 in the front side of which there is pivotally mounted a trigger 20 for manually actuating a vertically sliding sear 22 by conventional linkage (not shown).

Fixed to the front end of receiver 14, as by thread means, is a box-type frame mount 24 which forms a lateral opening 26. Mount 24 includes a rear plate 28 and a front plate 30 and centrally mounted therebetween is a rod 32 which is arranged parallel to the axis of receiver 14. Rotatingly mounted on rod 32 is a cylinder 34 which is provided with ten chambers 36 arranged symmetrically around the axis thereof and which are respectively arranged for receiving a cartridge 38. Receiver 14 is fixed to rear plate 28 adjacent the upper end thereof by coupling 40, and the breech end of a barrel 42 is matingly received by an opening in front plate 30 so that the axis of the barrel and receiver 14 are axially aligned. Chambers 36 are arranged to be in coalignment with barrel 42 and receiver 14 when indexed at a firing position, as hereinafter described. Barrel 42 is fixed to front plate 30 by a coupling 44. Operationally

2

disposed between front plate 30 and cylinder 34 is a torsion spring 46 which is loaded by turning the cylinder in a clockwise direction, see FIGS. 1 and 3, so as to drive the cylinder in a counterclockwise direction when free. Chambers 36 are formed so that, when cartridge 38 is fully seated therein, base 48 of case 50 of the cartridge is spaced slightly forward from the rear face of cylinder 34 to permit setback of the case approximately .060 to .080 inch before the base contacts rear plate 28 when the cartridge is discharged. A channel 51 extends radially from each of the chambers 36 to the outside periphery of cylinder 34 in the rear face thereof for a purpose which will be disclosed hereinafter.

Bolt assembly 16 includes a front member 52 and a rear member 54 both of which are of cylindrical configuration. Front member 52 and rear member 54 are provided with pairs of laterally opposed flanges 56 and 58, respectively, which are slidably received by mating ways 60 in the inside wall of receiver 14 to guide such front and rear members in their longitudinal travel. A compression spring 62 is disposed between the rear end of rear member 54 and a butt plate 64 mounted to the rear end of receiver 14 for biasing the rear member forwardly. A coil spring 66 having a compression resiliency less than that of spring 62 is located between front member 52 and rear member 54. A firing pin 68 is fastened at the rear end to rear member 54 so as to extend coaxially forward therefrom. The front end of the firing pin is provided with a striker portion 70 of smaller diameter which is contactable with a primer 72 in case 50 when in the firing position and the rear member is in the forward striking position. Provided through front member 52 is a stepped bore 74 for matingly receiving firing pin 68 so that the end of striking portion 70 extends from front member 52 for contact with primer 72 of cartridge 38 when indexed at the firing position.

The front end of front member 52 is cut down to form a tongue 76 which extends forwardly from a front wall 78 and which is of a rectangular configuration. Tongue 76 is extendable through an aperture 80 in rear plate 28 so as to have contact with base 48 of cartridge 38 at the firing position. Aperture 80 has the same cross-sectional dimensions as the cross-sectional area of tongue 76 and is designed to be longer than the thickness of rear plate 28 so that, when front wall 78 is in contact with the rear face of rear plate 28, cartridge 38 at the 12 o'clock firing station is positioned by the tongue at its forward fully seated position in the associated chamber 36. The vertical height of tongue 76 is greater than the diameter of chamber 36 at its mouth so that the tongue is partially received by the associated channel 51 which has sufficient depth to permit displacement of cartridge 38 to its fully seated position by the tongue. The width of channel 51 is slightly greater than that of tongue 76 and is provided with a right wall, see FIG. 8, which, when in contact with the tongue, indexes the respective chamber 36 at the firing position.

A pawl 84 is pivotally mounted in an accommodating vertically disposed recess 86, formed in the rear face of rear plate 28 to the right and below aperture 80 by means of a lateral pin 88. Pin 88 mounts pawl 84 approximately midway the length thereof so that the top end of the pawl, noted at 90, is contactable by front wall 78 for forward displacement. A tang 92 extends forwardly from the front side of the lower end at pawl 84 so as to be receivable in one of ten mating notches 94 which are formed symmetrically in the rear face of cylinder 34 around the axis thereof and positioned so as to be in respective association with corresponding chambers 36 as hereinafter described.

A spring 96 is operationally disposed between top end

99 and the inside wall of recess 86 to bias such top end outwardly and tang 92 inwardly so as to be pressed into one of the notches 94 when aligned therewith. Notches 94 are arranged so that, when tang 92 is received by one thereof the rotation of cylinder 34 by spring 46 is blocked to locate the associated chamber 36, which is the next successive chamber moving into firing position, slightly in advance of the firing position. When front member 52 is forwardly displaced to its battery position, so that front wall 78 thereof is in contact with front plate 30, pawl 84 is actuated by contact of the front wall with top end 90 to withdraw tang 92 from the associated notch 94 and thereby free cylinder 34 for rotation by spring 46 to where right side 82 of the associated channel 51 contacts tongue 76, thereby indexing the associated chamber 36 at the firing position.

Firing pin 68 is held cocked by sear 22 through the contact thereof with a wall 98 formed at the rear end of a channel 100 extending rearwardly from front face of rear member 54 along the underside thereof.

Operation

Thus, when firearm 12 is ready to be fired, firing pin 68 is held cocked by the engagement of wall 98 in rear member 54 with sear 22 and front member 52 is pressed forwardly by spring 66 to the battery position with cartridge 38 in chamber 36 at the firing station being held forwardly in its fully seated position by tongue 76. Also, tang 92 is held free of the notches 94 by the contact of front wall 78 with top end 90 of pawl 84. When trigger 20 is pulled and sear 22 is disengaged from wall 98 by conventional linkage (not shown), rear member 54 is freed to be displaced forwardly by spring 62 so that striker portion 70 impacts against primer 72 of the firing position cartridge 38 to cause discharge thereof.

The discharge sets case 50 back by blowback force to where base 48 contacts the front face of rear plate 48 and bolt assembly 16 is, consequently, energized for its operational functions. During the recoil displacement of bolt assembly 16, front member 52 and rear member 54 travel rearwardly together until the energy therein is absorbed by spring 62. When the energy in bolt 16 is reduced to zero, the transferred energy in spring 62 moves the bolt assembly forward in a counterrecoil stroke. During the initial portion of the counterrecoil stroke, wall 98 in rear member 54 makes engagement with sear 22 and the rear member is thereby held cocked while front member 52 continues forwardly to battery position under the bias of spring 66.

When front member 52 moved rearwardly from battery position, pawl 84 was freed to be pivoted by spring 96 so as to press tang 92 inwardly. Tang 92 contacts the rear face of cylinder 34 until tongue 76 is displaced rearwardly out of the associated channel 51. When tongue 76 becomes disengaged from the associated channel 51, cylinder 34 is freed to be rotated by spring 46 in a counterclockwise direction until tang 92 drops into the next succeeding one of the notches 94, whereby rotation of the cylinder is stopped with the next successive chamber 36 positioned slightly in advance of firing position.

When front member 52 is adjacent battery position during its counterrecoil travel, top end 90 of pawl 84 is contacted by front wall assembly 78 so as to remove tang 92 from associated notch 94, whereupon cylinder 34 is freed to continue rotation under the bias of spring 46 until tongue 76 is contacted by right side 82 of the associated notch to index the next successive chamber at the firing position.

From the foregoing it is clearly apparent that there is taught herein a combination firing and indexing device which is simple in design and positive in operation to make possible a revolver type firearm which is of sound construction yet which is inexpensive to manufacture because of the minimum number of parts required through

the operational cooperation of the firing and indexing devices.

Although a particular embodiment of the invention has been described in detail herein, it is evident that many variations may be devised within the spirit and scope thereof and the following claims are intended to include such variations.

I claim:

1. A revolver-type firearm including a rotatable cylinder with a plurality of chambers for respectively receiving a cartridge with a case for discharge therein, said chambers being respectively formed to permit set back of said case therein when said cartridge is discharged, and a bolt assembly arranged to be energized for reciprocation by set back of said case.

2. A revolver-type firearm including a rotatable cylinder having a plurality of chambers for respectively receiving a cartridge with a case for set back therein when said cartridge discharged, a bolt assembly having a firing pin, means in said bolt assembly engageable by a sear to cock said firing pin during reciprocation of said bolt assembly, means for positioning said cartridge in said chambers to permit set back of said case for energizing said bolt assembly for reciprocal displacement, and a pawl device disposed for operational cooperation with said bolt assembly to index said cylinder for positioning the chambers therein successively at a firing position.

3. A revolver-type firearm as defined in claim 2 including a spring arranged for biasing said bolt assembly towards said cylinder and wherein said bolt assembly includes a rear member acted upon by said spring and arranged to carry said firing pin, a front member including a bore to receive said firing pin and permit extension thereof through said front member for impact with said cartridge when in the firing position, and means on said front member arranged for operational cooperation with said pawl device for indexing said cylinder to position said chambers successively at the firing station.

4. A firearm including a receiver, a barrel, a cylinder, a torsion spring arranged to rotate said cylinder when energized, a cartridge including a case, a plurality of chambers symmetrically formed in said cylinder around the axis thereof, means for rotatably mounting said cylinder between said receiver and said barrel so that said chambers are successively alignable with said barrel at a firing position, said chambers being respectively formed so as to permit set back of said case therein from a fully seated position by discharge of said cartridge, a bolt assembly mounted in said receiver for sliding reciprocation therein and adapted to be energized for reciprocation by said case when set back, said bolt assembly including a firing pin arranged to be cocked by a trigger actuated sear during reciprocation of said bolt assembly, a spring disposed in said receiver for biasing said bolt assembly forwardly therein, and means cooperating with said bolt assembly and said torsion spring for indexing said cylinder to successively position said chambers at the firing position.

5. A firearm as defined in claim 4 wherein said means for mounting said cylinder between said receiver and barrel includes a box-type frame having a rear plate contactable by said case to limit the set back displacement thereof, and wherein said bolt assembly includes a tongue extending forwardly from a front wall through a mating aperture in said rear plate for contact with the base of said case in the firing position to hold said cartridge in the fully seated position when said front wall is in contact with said rear plate and to transfer set back displacement of said case by discharge of said cartridge to said bolt assembly so as to be energized for rearward travel in said receiver.

6. The firearm as defined in claim 4 wherein said means for rotatably mounting said cylinder includes a rear plate disposed between said receiver and said cylinder, and said bolt assembly includes a rear member for carrying said

firing pin, said rear member being acted upon by said spring for forward displacement in said receiver, means formed in said rear member for engagement by a sear for releasably holding said rear member in a cocked position, a front member, a stepped bore through said front member to permit extension of said firing pin therethrough for impact with said cartridge located at the firing position, a tongue extending integrally forward from a front wall on said front member for extension through a mating aperture in said rear plate for positioning said firing position cartridge at the fully seated position when said front wall is in contact with said rear plate, and a spring disposed between said front and rear members for biasing said front member forwardly relative to said rear member to effect contact between said front wall and said rear plate when said rear member is held in cocked position.

7. A firearm as defined in claim 6 wherein said means cooperating with said bolt assembly for indexing said cylinder includes a pawl pivotally mounted on a pin laterally disposed in said rear plate, said pawl including a tang extending from said pawl below said pin for releasable engagement with one of a plurality of notches in said cylinder equal to the number of chambers and respec-

tively corresponding thereto for stopping rotation of said cylinder to position the corresponding one of said chambers adjacent the firing position, a top end on said pawl positioned above said pin for contact by said front wall on said front member when said front wall is adjacent said rear plate to disengage said tang from the associated one of said notches to permit continued rotation of said cylinder by said torsion spring, a channel extending radially from each of said chambers in the rear face of said cylinder to permit the displacement of said cartridge to the fully seated position thereof by said tongue when said front wall on said front member is in contact with said rear plate, and a right side formed on each of said channels so as to be contacted by said tongue to stop rotation of said cylinder when the corresponding one of said chambers is located at the firing position after said tang is disengaged from the associated one of said notches.
